DYEING APPARATUS

Ernest A. Stienen, New York, N. Y.

Application November 19, 1936, Serial No. 111,593

5 Claims. (Cl. 8—19)

This invention relates to a dyeing apparatus.

The object of the invention is the production of dyeing apparatus with which hats or other objects are dyed the same color and shade, by maintaining them at all times during the operation of dyeing in the dye liquor. This condition is secured by dyeing said hats or objects in an operating tank having covers, the operative positions of which can be easily adjusted.

10 The second object of the invention comprises means wherewith the direction of the flow of the dye liquor can be reversed and thereby efficiently penetrate the hats or other objects operated upon.

15 The third object of the invention is the production of means wherewith any fumes generated during the process of dyeing can easily escape.

In the accompanying drawing Fig. 1 represents a top plan view of the dyeing apparatus and Fig. 2 shows a section of Fig. 1 on the line 2, 2.

20 The dyeing apparatus comprises the conical oval shaped dye liquor reversing container designated in its entirety by the numeral 20. The said container is indicated having the conical oval shaped wall 21, with the flange 22 at its upper end, and the lower portion of the wall 21 joins with the flat bottom 23. Drain piping 24 with the outlet valve 25 extends from the wall 21. Journal brackets 28, which may be provided with stuffing boxes, are indicated with the journal 25

30 bearings 29. The latter are fastened to the outer face of the wall 21 diametrically opposite each other. A bed plate 30 supports the journal brackets 28. A foundation 32 having the longitudinal gutter 33 and the cross gutter 34 supports the bed plate 30. The drain piping 24 leads to the gutter 34. An electric motor 38 having the armature shaft 39 is supported upon the bed plate 30. A directional relay 40, shown only diagrammatically, is provided for the electric motor 38. A 40 propeller shaft 42 extends through the journal bearings 29 and has fastened thereto the propeller 43.

An operating tank is designated in its entirety by the numeral 50. The tank 50 comprises the bottom wall 51, having a plurality of perforations 52. The wall 51 is supported upon and fastened to the flange 22. An oval shaped vertical wall 54 is supported upon the wall 51 and the angle iron 55 connects the walls 51 and 54 and the flange 22. 50 At the upper end of the wall 54 is indicated the return shaped flange 58, and the angle iron 59 is interposed between the wall 54 and the said flange 58 and fastened thereto.

A top cross wall is indicated at 60 with the opening 61. A vent-funnel 62 extends up from

the wall 60 over its opening 61. The upper end of the funnel 62 is provided with the reinforcing band 63, and from the latter extend eyelets 64. To each of the latter is fastened one end of a supporting chain 65. Angle irons 67 extend crosswise upon the cross wall 60 and are fastened thereto. The cross wall 60 is fastened to the top of the tank 50 by means of the bolts 68.

To the cross wall 60 are hinged a pair of outer covers, each designated in its entirety by the numeral 70, by means of hinge connections 71. Each of the covers 70 has extending therethrough an opening 72, and has formed therewith a plurality of depressions 73 to form strengthening ribs. A pair of handles 74 extend up from each outer cover 10 70, and each of the latter is strengthened with the angle iron 75. From the outer face of each of the covers 70 extends a supporting hook 78 and the fork shaped clamping hook 79. From the bottom face of each cover 70 extend a pair of 20 journal brackets 83.

A pair of intermediate or inner suspended covers are each indicated in its entirety by the numeral 85. Each of the covers 85 on its inner side is provided with the upwardly extending curved 25 portion 86 having the edge 87. The said edges 87 are spaced from each other to form a vent opening 88. The curved portions 86 are provided to prevent injury to the objects dyed when the covers 85 are moved to different positions. The 30 outer end of each cover 85 is indicated at 89. An eye bolt 90 extends up from each cover 85 adjacent to its outer end.

From the upper face of each cover 85 extend a 35 pair of journal brackets 92.

Four links are each indicated at 95. Each of said links has its upper end in hinged connection with one of the journal brackets 83 by means of the pin 93 and its lower end is hinged to one of the journal brackets 92, by means of the pin 94. 40

It will be noted that the pins 94 are closer to the vertical axis of the apparatus than the pins 93, and thereby the links 95 are positioned in inclined positions, when the inner covers 85 are in their operative positions. By reason of the centers 45 of the pins 93 being horizontally spaced from the centers of the pins 94 toward the outer ends 89 of the covers 85, the said covers are forced to position said ends 89 to bear against the inner end face portion of the wall 54 of the operating tank 50. By this means there is prevented any considerable leakage between the said ends 89 and the adjacent face of the wall of the operating tank 50.

A chain 96 extends from each eyebolt 90, leads 55

through the adjacent opening 72 in its cover 70. The chains 96 are adjustably clamped in different positions in the adjacent forked shaped clamping hooks 79 to tilt the covers 85 to different 5 positions.

To operate the dyeing apparatus the outer covers 70 are lifted to their vertical positions as indicated in dotted lines at 70a, by means of the handles 74, and are held in place by connecting 10 the supporting chains 65 to the supporting hooks 78. By this means the inner covers 85 are also lifted to their raised positions as indicated in dotted lines at 85a.

The operator then charges the operating tank 15 50 with the hats or other objects to be dyed, and dye liquor to about the level of the line 100 is poured into the apparatus. The dye liquor will flow to the reversing container 20 through the perforations 52 of the wall 51. Next the covers 20 70 and 85 are lowered as shown in full lines in Fig. 2. The electric motor 38 is now started, by means of which the propeller 43 is turned and the dye liquor flows from the container 20 to the operating tank 50, through the perforations 52 at

25 one side of the wall 51, in the direction of the arrows 105, and penetrates the hats or other objects to be dyed in the said operating tank 50 to dye the same. The dye liquor returns to the reversing container 20 at the opposite side thereof. 30

The circulation of the dye liquor from the container 20 to and through the operating tank 50 is repeated for a predetermined number of times. The rotation of the electric motor 38 is then automatically reversed by the directional 35 relay 40, by means of which the propeller 43 is turned in the reverse direction for a predetermined number of times. The dye liquor now flows in the direction reverse to that shown by the arrows 105, and the hats or other objects 40 are again penetrated by the dye liquor. The electric motor 38 by means of the relay 40 is then reversed to its original direction and the steps are repeated until the hats or other objects are thoroughly penetrated and dyed.

45 If it is desired to drain the apparatus the outlet valve 25 is opened and the dye liquor will flow through the drain pipe 24 into the cross gutter 34 and then will be discharged into the longitudinal gutter 33 to a tank or other container 50 as desired.

Attention is called to the fact that the hats or other objects dyed remain at all times during the dyeing in the operating tank 50 completely immersed in the dye liquor in said operating tank, 55 to secure the same reaction with the dye liquor to dye all the hats or other objects the same shade and color. In case the level of the dye liquor falls below the level indicated at 100 and below the level of the inner covers 85, the operator lowers said covers 85 by lifting the chains 60 96 from the fork shaped clamping hooks 79 and lowers the said inner covers 85 to a position as indicated at 85a, to maintain all the hats or other objects below the top level of the dye liquor in 65 this position as well as in the original position of the inner covers 85, the suspension of said covers 85, by the links 95 tends to position the ends 89 of the covers against the inner end faces of the wall 54. The vent opening 88 between the 70 edges 87 of the inner covers 85, the opening 61 and the vent funnel 62 permits the escape of any fumes generated in the apparatus.

Various modifications may be made in the invention and the present exemplification is to be

taken as illustrative and not limitative thereof. Having described my invention, I claim:

1. In a dyeing apparatus the combination of an operating tank for objects to be dyed, covers suspended in said tank, means to locate said 5 covers in different positions and means to automatically force the opposite outer ends of the covers against the adjacent face portion of the operating tank.

2. In a dyeing apparatus the combination of an 10 operating tank for objects to be dyed, outer covers hinged to the top of the tank, inner covers for the tank, suspension means between the outer portions of the inner covers and the outer covers, suspension means between the inner portions of 15 the inner covers and the outer covers, the latter suspension means functioning to force the outer end portions of the inner covers against the inner end face portions of the operating tank, the suspension means being adapted to tilt the inner covers to 20 different positions to at all times cover objects operated upon, to dye the same, in said operating tank, and means to circulate a dye liquor through the operating tank.

3. In a dyeing apparatus the combination of 25 a dye liquor reversing container, an operating tank above the reversing container for objects to be dyed, a wall having perforations between the reversing container and the operating tank, means in the reversing container to circulate a 30 dye liquor therefrom through the operating tank, a pair of outer covers hinged to the top of the operating tank, inner covers in the operating tank, and suspension means between the outer 35 covers and the inner covers to position the latter in different tilted positions and at the same time force the outer ends of the inner covers against the inner end face portions of the operating tank.

4. In a dyeing apparatus the combination of a dye liquor reversing container, an operating tank 40 adjacent to the reversing container for hats or other objects to be dyed, a wall having perforations between the reversing container and the operating tank, a top cross wall for the operating tank, a pair of outer covers hinged to said 45 cross wall, a pair of links having their upper ends in hinged connection with each outer cover, a chain adjustably suspended from each outer cover, inner covers, each having one end in hinged connection with the lower ends of a pair 50 of said links and the other end of each inner cover adjustably suspended by one of said chains and means to circulate a dye liquor from said reversing container through said operating tank to dye said hats or other objects.

5. In a dyeing apparatus the combination of a dye liquor reversing container, an operating tank above the reversing container for hats or other objects to be dyed, a wall having perforations between the reversing container and the operating tank, a pair of outer covers hinged to the top end of the operating tank, a pair of links having their upper ends in hinged connection with each outer cover, said links normally inclining downwardly toward the vertical axis of 60 the apparatus, a chain adjustably suspended from each outer cover, inner covers, each having one end in hinged connection with the lower ends of a pair of said links and its other end adjustably suspended by one of said chains and means 65 to circulate a dye liquor from the reversing container through said operating tank to dye said hats or other objects.
